(57) **CLAIM**

The ornamental design for a buffing device, as shown and described.

DESCRIPTION

FIG. 1 is a perspective view of buffing device showing my new design.

FIG. 2 is a front view thereof.

FIG. 3 is a rear view thereof.

FIG. 4 is a right end view thereof.

FIG. 5 is a left end view thereof.

FIG. 6 is a top view thereof; and,

FIG. 7 is a bottom view thereof.

The broken line showing of a cord in FIGS. 1-3 and 5-7 is included for the purpose of illustrating portions of the Buffer and forms no part of the claimed design.

1 Claim, 7 Drawing Sheets

FIG. 1

FIG.2

FIG.3

FIG.4

FIG. 5

FIG.6

FIG. 7
